DESIGN FOR A COMBINED BOTTLE AND STOPPER

Paul H. Ganz, New York, N. Y., assignor to D. Lisner & Co., New York, N. Y., a corporation of New York

Application July 28, 1934, Serial No. 52,727

Term of patent 14 years

To all whom it may concern:

Be it known that I, PAUL H. GANZ, a citizen of the United States, residing in the city, county, and State of New York, have invented a new, original, and ornamental Design for a Combined Bottle and Stopper, of which the following is a specification, reference being had to the accompanying drawing, forming part thereof.

Figure 1 is an exploded view in perspective showing a combined bottle and stopper embodying my new design;

Figure 2 is a plan view of the stopper, the view being taken on the line 2—2 of Figure 1 looking in the direction of the arrows; and

Figure 3 is a plan view of the bottle, the view being taken on line 3—3 of Figure 2, looking in the direction of the arrows.

I claim as my invention:

The ornamental design for a combined bottle and stopper as shown.

PAUL H. GANZ.
